C. H. COLBURN

POWER DRIVEN SLEIGH

Filed Oct. 25, 1921.

Inventor
CHARLES H. COLBURN

By *J. L. Polachek* Attorney

UNITED STATES PATENT OFFICE.

CHARLES H. COLBURN, OF HAMLIN, NEW YORK.

POWER-DRIVEN SLEIGH.

Application filed October 25, 1921. Serial No. 510,336.

To all whom it may concern:

Be it known that I, CHARLES H. COLBURN, citizen of the United States, residing at Hamlin, in the county of Monroe and State 5 of New York, have invented certain new and useful Improvements in Power-Driven Sleighs, of which the following is a specification.

This invention relates generally to sleighs 10 having more particular reference to a power driven sleigh.

The invention has for an object to provide the sleigh with an air propeller capable of being swung bodily for steering the sleigh.

Another object is to connect the propeller 15 with a steering runner whereby both will be swung in unison.

Another object relates to the provision of 20 novel means for lowering running wheels below the sleigh runners when desired.

For further comprehension of the invention, and of the objects and advantages thereof, reference will be had to the following description and accompanying drawings, 25 and to the appended claim in which the various novel features of the invention are more particularly set forth.

Fig. 1 of the drawings is a plan view of a 30 sleigh having the invention embodied there- in.

Fig. 2 is a side view thereof.

Fig. 3 is a transverse section on the line 3—3 of Fig. 2.

As here shown my improved sleigh comprises a body 10 of suitable shape and provided with a seat 11 located in a cockpit 12. This body is mounted on a front pair of runners 13 and a single, centrally located rear runner 14, the front runners being fixed 35 while the rear runner is dirigible, being held in place by a king-bolt 15. This king-bolt 40 15 has an arm 16 fixed to the upper end thereof, this arm being connected by the links 17 and lever 18 to an arm 19 fixed to a swinging frame 20 which supports an air propeller 21 by which the sleigh is driven.

The propeller 21 is driven by a motor 23 mounted in the front portion of the body 10, the propeller being fixed on a horizontal 50 stub shaft 24 on which is a bevel gear 25 meshing with a like gear 26 on the upper end of a vertical shaft 27. A second bevel gear 28 on the lower end of shaft 27 meshes with a bevel gear 29 on the crank shaft of 55 the motor 23.

The swinging frame 20 has the shafts 25

and 27 journaled therein and is here shown as pivotally supported, on an axis co-incident with that of shaft 27, by a pair of brackets 32 fixed to the motor 23. As will 60 be apparent, when frame 20 is swung to one side or the other, the direction in which shaft 24 extends will be varied. To accommodate the shaft 24 and the portion of frame 20 in which it is mounted, the front 65 end of the body 20 is provided with a slot 33.

To swing the frame 20, a handwheel 35 is mounted on one end of a steering shaft 36, the opposite end of this shaft having fixed thereon a spur pinion 37 meshing with rack 70 teeth 38 on the top face of a transverse bar 39 slidably supported in ears 40. The forward face of this bar is also provided with rack teeth 41 engaging a spur gear 42 fixed on frame 20. 75

As will be apparent, when the handwheel 35 is turned, the rack bar 39 will be moved, and will cause frame 20 to swing, changing the direction of pull of the propeller 21. Likewise, by reason of the connection between arm 19 fixed to frame 20, and arm 16 80 fixed to the king-bolt 15, the rear runner 14 will be turned in a direction opposite to that in which the propeller swings.

To enable the sleigh to be driven on bare 85 ground when necessary, I provide two pairs of front wheels 45 which are mounted on the lower ends of pivoted arms 46 operated by toggle links 47, these toggle links being operated by a thrust bar 48 slidable in 90 guides 49 in the sleigh body 10 and connected by a link 50 to a hand lever 51 provided with usual locking means as indicated at 52. By employing the toggle link device just described I am enabled to obtain a high leverage 95 in forcing the wheels 45 below the runner to raise the latter from the ground. In connection with the back runner 14 I fix thereto a pair of oppositely projecting pins 54 on which wheels 55 may be mounted 100 when desired, the back of the sleigh being easily lifted by hand to secure these wheels in place.

It is believed that the manner of operation and use of my improved sleigh will be readily understood from the above description and that no further detailed description is needed. It is to be understood that various changes and modifications might be made in the construction herein disclosed without departing from the spirit and scope of the invention as defined in the appended claim. 110

Having thus described my invention what I claim as new and desire to protect by Letters Patent of the United States is as follows:

- 5 In a sleigh, a runner at one end thereof, an air propeller at the opposite end, vertical members around which said runner and propeller are adapted to swing, laterally projecting arms fixed to said vertical members,

a pair of links connected at one end one to each of said arms, and a lever fulcrumed between its ends and having the said links connected respectively to opposite ends thereof whereby said runner and propeller are caused to swing oppositely in unison. 10

In testimony whereof I have affixed my signature.

CHARLES H. COLBURN.
